UNITED STATES PATENT OFFICE

146,832

DESIGN FOR A BUFFET CHAFING DISH

Daniel C. O'Connell, New York, N. Y., assignor to Sterno, Inc., a corporation of New York

Application January 16, 1946, Serial No. 125,618

Term of patent 14 years

(Cl. D44—15)

To whom it may concern:

Be it known that I, Daniel C. O'Connell, a citizen of the United States, residing at 840 Grand Concourse, New York, New York, have invented a new, original, and ornamental Design for a Buffet Chafing Dish, of which the following is a specification, reference being had to the accompanying drawing, forming part thereof, in which:

Fig. 1 is a perspective view of a buffet chafing dish embodying my new design; and

Fig. 2 is a top plan view thereof.

I claim:

The ornamental design for a buffet chafing dish, as shown.

DANIEL C. O'CONNELL.
